UNITED STATES PATENT OFFICE.

HARRY S. FOLGER, OF CHICAGO, ILLINOIS.

REVERSIBLE BLANK FOR STAMP-MOUNTS.

1,142,562.

Specification of Letters Patent. Patented June 8, 1915.

Application filed October 10, 1914. Serial No. 865,994.

To all whom it may concern:

Be it known that I, HARRY S. FOLGER, a citizen of the United States of America, and a resident of Chicago, county of Cook, and State of Illinois, have invented certain new and useful Improvements in Reversible Blanks for Stamp-Mounts, of which the following is a specification.

My invention relates to reversible blanks for stamp mounts, and has for its object the production of a sheet metal blank which may be bent in either of two ways to form either of two different kinds of stamp mount, both of which would have a card-holding flange on which may be secured a printed slip to indicate the character of the stamp secured to the mount.

In the accompanying drawings Figure 1 is a plan of the blank which is stamped from sheet metal and which subsequently may be bent to form either kind of mount; Fig. 2 is a side elevation of a plain mount formed from the blank and having the stamp, hand and indicating card attached thereto; Fig. 3 is a side elevation of a cushion holding mount formed from the blank and having a cushion, a stamp, a handle and an indicating card attached thereto; Fig. 4 is an enlarged transverse section on line 4-4 of Fig. 2; and Fig. 5 is an enlarged transverse section on line 5-5 of Fig. 3.

In Fig. 1, A is a rectangular plate having its corners cut out as shown at *a*. As so formed the space inclosed by the dotted lines connecting the adjacent reentrant angles represents the surface to which is to be connected the stamp or the cushion which lies between the stamp and the mount. Or, described in a different way, that part of the plate A which is bounded by the dotted lines is a rectangle having rectangular lips B, C, D and E projecting from its four edges. The lips B, C and D are of the same width, which width is preferably a trifle less than the thickness of the cushion to be used when the mount is to be used as a cushion holding mount. The fourth lip E is somewhat wider than the other lips, the width being determined by the desired width of the printed slip to be held by it.

In forming the mount from the blank shown in Fig. 1, the lips B, C, and D are bent, along the adjacent dotted lines, to a position perpendicular to the main body of the blank so that these three lips form three sides of a box, the main body of the blank

representing the top or bottom of the box according to the position in which it is held. The lip E is then either bent to form the fourth side of the box, or in the opposite direction to form a flange perpendicular to the main body. In the first case the mount is a mount for receiving a plain stamp on the side of the plate A opposite the flanges. (Figs. 2 and 4). In the second case a cushion is secured inside of the box and the stamp is secured to the lower face of the cushion. (Figs. 3 and 5).

In the center of the blank A is an oval or flat sided hole F. An ordinary wood screw G, flattened on the stem adjacent to the head, is then forced into this hole, and the handle H is mounted upon the screw. In the mount for a plain stamp, the handle H is located inside of a four-sided box, as shown in Fig. 4. In the mount for a cushion stamp, the handle is located on the back of a three sided box, the fourth side being open as shown in Fig. 5.

In Fig. 1 the dotted line separating the lip E from the main body A is shown slightly removed from the corners of the adjacent reentrant angles *a*. This is to indicate that the line of bend for the lip E is slightly removed from the corners *a* so that when this lip forms the fourth side of a box there will be a small space K (Fig. 4) between the ends of this flange and the adjacent ends of the flanges B and D. This is for the purpose of permitting the indicating card, which in this case is a paper band M, to be slipped over the upwardly projecting flange E.

The stamp S is secured, by cementing or otherwise, to the body A opposite the handle H. In Fig. 4, this connection is direct. In Figs. 3 and 5, a cushion T is inserted between the stamp and the body A.

In mounts of this character, a card holding flange E, or its equivalent, is a desirable thing. In the arrangement shown in Fig. 4, the flanges B, C and D are simply stiffening flanges which makes it possible to use thin metal for the mount. In Fig. 5, the flanges B, C and D are not only stiffening flanges but are sides of a box for containing the cushion T. A cushion not at all inclosed would be liable to dislodgment, but a cushion inclosed on three sides is sufficiently secure for all ordinary purposes.

What I claim is:

1. In a blank for a stamp mount consist-

ing of a rectangular piece of sheet metal having integral lips or flanges extending from the edges thereof, three of said flanges being of the same width and the fourth flange being of greater width than the other flanges.

- 5 2. A flange for a stamp mount consisting of a rectangular piece of sheet metal having corners *a* removed therefrom to produce projecting lips which may be bent into flanges perpendicular to the main body of the blank, one of said projecting lips being of a different width from the other three lips.
- 10 3. A blank for a stamp mount consisting

of a rectangular piece of sheet metal having 15 lips which may be bent up to form the four sides of a box, one of said lips being of a different width from the other lips and the back or bottom of the box being provided with a center hole F for the reception of a 20 handle-holding screw.

Signed at Chicago, Illinois this 8th day of October 1914.

HARRY S. FOLGER.
